(57) **CLAIM**

The ornamental design for an audio speaker enclosure, as shown and described.

DESCRIPTION

FIG. 1 is a side elevation view of a first embodiment of my ornamental design for an audio speaker enclosure;

FIG. 2 is a top view of the first embodiment of the ornamental design for an audio speaker enclosure of the invention;

FIG. 3 is a bottom view of the first embodiment of the ornamental design for an audio speaker enclosure;

FIG. 4 is a top perspective view of the first embodiment of the ornamental design for an audio speaker enclosure;

FIG. 5 is a bottom perspective view of the first embodiment of the ornamental design for an audio speaker enclosure;

FIG. 6 is a side elevation view of a second embodiment of an ornamental design for an audio speaker enclosure;

FIG. 7 is a top view of the second embodiment of the ornamental design for an audio speaker enclosure;

FIG. 8 is a bottom view of the second embodiment of the ornamental design for an audio speaker enclosure;

FIG. 9 is a top perspective view of the second embodiment of the ornamental design for an audio speaker enclosure;

FIG. 10 is a bottom perspective view of the second embodiment of the ornamental design for an audio speaker enclosure;

FIG. 11 is a side elevation view of a third embodiment of an ornamental design for an audio speaker enclosure;

FIG. 12 is a top view of the third embodiment of the ornamental design for an audio speaker enclosure;

FIG. 13 is a bottom view of the third embodiment of the ornamental design for an audio speaker enclosure;

FIG. 14 is a bottom perspective view of the third embodiment of the ornamental design for an audio speaker enclosure;

FIG. 15 is a top perspective view of the third embodiment of the ornamental design for an audio speaker enclosure;

FIG. 16 is a side elevation view of a fourth embodiment of an ornamental design for an audio speaker enclosure;

FIG. 17 is a top view of the fourth embodiment of the ornamental design for an audio speaker enclosure;

FIG. 18 is a bottom view of the fourth embodiment of the ornamental design for an audio speaker enclosure;

FIG. 19 is a bottom perspective view of the fourth embodiment of the ornamental design for an audio speaker enclosure; and,

FIG. 20 is a top perspective view of the fourth embodiment of the ornamental design for an audio speaker enclosure.
